CHESTER L. BALDWIN, OF ALMOND, WISCONSIN, ASSIGNOR OF ONE-HALF TO MERLE CASEY, OF ALMOND, WISCONSIN.

GRINDING-TOOL FOR GAS-ENGINE VALVES.

1,104,863.

Specification of Letters Patent.

Patented July 23, 1914.

Application filed July 30, 1913. Serial No. 781,963.

To all whom it may concern:

Be it known that I, CHESTER L. BALDWIN, a citizen of the United States, and a resident of Almond, in the county of Portage 5 and State of Wisconsin, have invented a new and Improved Grinding-Tool for Gas-Engine Valves, of which the following is a full, clear, and exact description.

This invention relates to a tool for enabling gas engine valves to be ground on their seats.

The invention has for its general objects to improve and simplify the construction and operation of tools of this character so 15 as to be comparatively inexpensive to manufacture, reliable and efficient in use and readily adjustable for various sizes and forms of valves.

Another object of the invention is the provision of a hand tool having a valve-engaging head connected with a stem or shaft to which rotation is imparted by one hand of the operator through suitable means, while pressure is exerted through the tool on the 25 valve by the other hand so as to hold the valve in grinding relation to its seat.

Another object of the invention is the provision of adjustable and removable engaging means on the head of the tool and 30 also steadyng devices on the head which are adjustable to engage with the valve.

Another object is the provision of a spirally threaded shaft or stem with which engages a threaded sleeve that is reciprocated on the stem so as to rotate the latter alternately in opposite directions to effect the grinding action.

With these objects in view, and others as will appear as the description proceeds, the 40 invention comprises various novel features of construction and arrangement of parts which will be more fully described herein-after and set forth with particularity in the claims appended hereto.

In the accompanying drawing, which 45 illustrates one embodiment of the invention, and wherein similar reference characters are employed to designate corresponding parts throughout the several views, Figure 50 1 is a side view of the tool with the upper handle in section; Fig. 2 is a sectional view on the line 2—2 of Fig. 1; Fig. 3 is a bottom plan view of the head of the tool; and Fig. 4 is a sectional view on the line 4—4 55 of Fig. 1; Fig. 5 is a side view of a modified

form of tool; Fig. 6 is a central vertical section thereof; Fig. 7 is a bottom plan view; and Fig. 8 is a section similar to Fig. 6, showing a different style of valve-engaging means applied to the head of the tool. 60

Referring to the drawing, A designates the head of the tool which is a disk-like body having in its under side guideways 1 and 2 which are disposed in a diametrical line with a partition 3 between them, the walls 65 of the guideways being undercut to provide shoulders 4. In the guideways are bits 5 and 6 which slide inwardly and outwardly by the turning of a rotary element 7 which has right and left hand threads 8 and 9 that engage in threaded openings 10 and 11 in the bits 5 and 6, respectively. The middle portion 12 of the threaded element 7 is 70 smooth and reduced to provide shoulders 13, and this reduced portion 12 is journaled in 75 an opening 14 in the partition 3. Thus by turning the threaded element 7 the bits 5 and 6 can be moved inwardly or outwardly so that the valve-engaging portions 15 of the bits will be in proper relation to engage 80 in sockets or the like in the top of the valve to be ground.

The head A is adapted to be rotated by a shaft or stem B which is connected with the head by a universal joint C, which joint 85 C consists of a block or connecting element 16 which is set between lugs 17 on the head A and united therewith by journals or pins 18 fastened to the block 16, and spanning the block are the bifurcations 19 of the stem B, 90 there being a pin 20 passing through the block 16 and bifurcations 19 to hingedly connect the block with the stem. The pin 20 is disposed at right-angles to the journals 18, so that universal movement is provided 95 between the head A and stem B. The stem B has a spiral groove or thread 21 of coarse pitch, and slidably longitudinally of the stem is a sleeve 22 that has a pin 23 that projects into the groove 21, so that as the 100 sleeve 22 moves up and down on the stem B the latter is rotated in one direction and then in the other, there being on the sleeve 22 a handle 24 whereby the operator can conveniently actuate the sleeve. On the upper end of the stem B is a rest or handle 25 that has a central metal-lined opening 26 through which the upper end of the stem passes, said upper end being reduced to form a shoulder 27 that is engaged by the handle 110

25, and threaded on the upper end of the stem is a nut 28 which holds the handle attached to the stem. The handle 25 is adapted to be grasped by one hand to steady the tool and apply pressure in a direction to force the valve against its seat while the other hand of the operator grasps the handle 24 to move the sleeve rapidly up and down, whereby the valve is given a rotary movement first in one direction and then in the opposite direction.

To steady the head A with respect to the valve the head is provided with screws or equivalent devices 29 which are threaded in 15 openings 30 in the head, the upper ends 31 of the screws being knurled so that they can be easily turned.

In applying the tool to a valve the bits thereof are adjusted so as to engage in the 20 depressions, slots or other means 32 provided in the top surface of the valve, and then the screws 29 are turned in such a direction that both of them will bear on the upper surface of the valve. With this arrangement the tool has a four-point contact 25 with the valve, namely, the two bits 5 and 6 and steadyng screws 29. The head of the tool is so proportioned, that it can be readily inserted in the cap opening in the valve 30 chamber, and the stem B will of course extend out of the valve chamber where the handles 20 and 25 can be conveniently grasped.

The head A' is in general aspects the 35 same as the head A in Figs. 1 and 2, with the exception that the transverse partition or bearing 3 is dispensed with and a single diametrical slot 1^a extends entirely across the bottom of the head, the side walls of the 40 slot being undercut. At the center of the slot is a recess or seat 35 which serves as in Fig. 6 to hold the bit 36 centrally in place, or, as shown in Fig. 8, to hold a removable bearing 37 for the right and left-hand screw 45 38 which moves the bits 5^a and 6^a inwardly and outwardly. The bit 36 has an engaging edge 39 similar to a screw driver and is adapted to engage in a slot in the valve to be ground. When a centrally-disposed bit 50 is employed, as shown in Figs. 5 to 7 inclusive, four steadyng screws 40 are provided in the head A', and these screws are so adjusted that their lower ends will lie in the same plane and bear on the valve to be 55 ground, but the adjustment of the screws is such that the edge 39 of the bit 36 will project downwardly below the plane in which the lower ends of the screws lie, so as to enable the bit 36 to be engaged in the slot 60 of the valve while the screws rest on the surface of the latter. When the bits are to be employed, as shown in Fig. 8, the screws 40 extending through the ends of the slot or guideway 1^a are removed so as to provide for the adjusting screw 38 for the bits

5^a and 6^a. In the bit 36 is a chamber 41 that contains a spring 42, which spring presses upwardly a key 43 in the form of a ball, so that it will enter the recess 35, whereby lateral displacement of the bit 36 70 in the guideway 1^a is prevented. The conversion of the tool from a single to a double bit valve-engaging means is very simply accomplished and yet the tool is reliable in operation when used in either manner.

From the foregoing description taken in connection with the accompanying drawings, the advantages of the construction and method of operation and of the device shown will be readily understood by those 85 skilled in the art to which the invention appertains, and while I have described the principle of operation, together with the device which I now consider to be the best embodiment thereof, I desire to have it understood that the device shown is merely illustrative and that such changes may be made when desired as are within the scope of the appended claims.

Having thus described my invention, I 90 claim as new and desire to secure by Letters Patent:

1. A valve grinding tool comprising a head, valve-engaging means thereon, independently adjustable devices on the head 95 engaging the valve and separate from the said means to steady the head with respect to the latter, and means connected with the head for turning the same.

2. A tool of the class described comprising 100 a head, adjustable valve-engaging bits thereon, adjustable devices on the head for engaging the valve to steady the head with respect thereto, and means connected with the head for turning the same.

3. A tool of the class described comprising 105 a head, a pair of adjustable bits thereon, a pair of steadyng devices adjustably mounted on the head for engaging the valve and co-operating with the bits to form a four-point contact between the head and valve, and means connected with the head for turning the same.

4. A tool of the class described comprising 110 a head, a pair of bits on the head and adjustable in a diametrical line toward and from the center of rotation, a pair of screws arranged in a diametrical line at right-angles to the line of the bits and adapted to engage the valve for steadyng the head with respect thereto, and means connected with the head for turning the same.

5. A tool of the class described comprising 115 a head, steadyng devices mounted on the head at opposite sides of the center thereof for engagement with the valve, valve-engaging means placed at opposite sides of the center of the head thereon, a shaft having a screw thread, a universal connection 120 between the shaft and head, a handle 130

swiveled on the upper end of the shaft, and a sleeve slideable on the shaft and engaging the thread thereof to impart rotation to the shaft.

5. A valve grinding tool comprising a head, removable valve-engaging means thereon, and a plurality of devices adjustably mounted on the head for engaging the valve to steady the tool with respect thereto.

In testimony whereof I have signed my name to this specification in the presence of two subscribing witnesses.

CHESTER L. BALDWIN.
